Morsell & Keeney,
ATTORNEYS.

UNITED STATES PATENT OFFICE.

HENRY SEELMAN, OF MILWAUKEE, WISCONSIN.

EXTENSION-COVER HOLDER.

Application filed September 24, 1921. Serial No. 502,970.

To all whom it may concern:
 Be it known that I, HENRY SEELMAN, a citizen of the United States, and resident of Milwaukee, in the county of Milwaukee and State of Wisconsin, have invented new and useful Improvements in Extension-Cover Holders, of which the following is a description, reference being had to the accompanying drawings, which are a part of this specification.

This invention relates to improvements in extension cover holder for valuable papers, etc.

Ordinary covers for holding papers of value are constructed to hold approximately a fixed amount of paper and if the aggregate amount of paper is thicker or thinner than the amount the cover was adapted to contain, the edges of the cover will not extend over the paper or the covers will extend over the papers to too great an extent and prevent the proper closing of the holder.

It is one of the objects of the present invention to overcome the before mentioned objectionable features and provide an extension cover holder which may be easily adjusted to hold a number of papers of greater or less thickness.

A further object of the invention is to provide an extension cover holder having a plurality of pockets in the form of envelopes, which may be easily increased or decreased in number as desired.

A further object of the invention is to provide an extension cover which is of simple construction, is strong and durable and is well adapted for the purpose described.

With the above and other objects in view the invention consists of the improved extension cover holder and its parts and combinations as set forth in the claims, and all equivalents thereof.

In the accompanying drawings in which the same reference characters indicate the same parts in all of the views:

Fig. 1 is a perspective view of the improved extension cover;

Fig. 2 is a transverse sectional view thereof taken on a larger scale;

Fig. 3 is a side view on a smaller scale of one portion of the holder with the envelopes or pockets shown removably secured thereto;

Fig. 4 is a side view in open position and on a smaller scale, of the other portion of the holder; and

Fig. 5 is a sectional detail view on a larger scale taken on line 5—5 of Fig. 3.

Referring to the drawing, the numeral 8 indicates the main cover and 9 the extension cover of the improved holder. The main cover 8 is of double thickness and the edge portions of the inner part 8' are secured to the edges of the outer part 9 with the exception of the rear edge and a medial portion of the front edge to form a rear edge extension cover opening 10 and a medial front edge strap opening 11. An outer portion 9' of the extension cover 9 of a size corresponding to the size of the main cover 8 is reinforced by a part 9" to form a somewhat firm structure whereas the extension part 12 is of a flexible nature so that it can easily flex in forming the extensible back portion 12'. The flexible portion 12 of the extension cover 9 is adapted to freely enter the rear edge opening 10 and slide between the inner and outer parts of the main cover 8. A strap 13 having one end sewed to a medial edge portion of the flexible part of 80 the extensible cover extends through the front edge opening 11 of the main cover and is adjustably engaged by a buckle 14 of any desirable form mounted on the outer side of the reinforced portion of the extensible cover. As thus constructed and assembled the space between the two covers may be increased or diminished to hold papers of varying thicknesses by adjustably sliding in or out of the main cover, the flexible portion 12 of the extensible cover 9. 85

Pocket members 15 in the form of envelopes are preferably provided for holding papers of value and these envelopes are removably secured to the main cover member 95 by a string or flexible member 16. Said string is adapted to be threaded through metal eyelets 17 mounted in the corner portions of the envelopes and also through metal eyelets 18 mounted in pairs in the opposite end portions of the inner part 8' of the main cover part 8. The opposite ends of the string are adjustably tied together as indicated by the numeral 19 to accommodate a varying number of envelopes and envelopes which vary in thickness. 100

From the foregoing description it will be seen that the extension cover holder is of very simple construction and is well adapted for the purpose described.

I claim as my invention:

1. An extension cover holder, comprising

2

a main cover member of two thicknesses of material, an extensible cover member having a flexible portion and a firm portion, the flexible portion adjustably extending between the two thicknesses of material of the main cover member for adjusting the distance apart of the two cover members, one of said cover parts having paper-holding means, and means for holding the cover members in closed position.

2. An extension cover holder, comprising a main cover member of two thicknesses of material, an extensible cover member having a firm portion which forms the cover proper and a flexible portion which adjustably extends between the two thicknesses of material of the other cover member for adjusting the distance apart of said cover members, paper-holding means carried by one of the cover members, and means connected to the flexible portion of the extensible member for holding the two cover members together.

3. An extension cover holder, comprising a main cover member formed of two thicknesses of material joined together at their opposite ends, an extensible cover member having a firm portion which forms the cover proper and a flexible portion which slidably extends between the two thicknesses of material of the other cover member for adjusting the distance apart of said cover members, means for removably connecting paper-holding members to one of the cover members, and a strap member connected to the flexible portion of the extensible member and adjustably connected to the firm portion of said extensible member for holding the cover member in closed position.

4. An extension cover holder, comprising a main cover member formed of two thicknesses of material joined together at their opposite ends, the inner edge of the inner thickness of material having openings, an extensible cover member having a firm por-

tion which forms the cover proper and a flexible portion which slidably extends between the two thicknesses of material of the other cover member for adjusting the distance apart of said cover members, envelopes removably positioned between the covers and having openings registering with the openings of the inner thickness of material of the main cover, a flexible means extending through the openings of the envelopes and the inner thickness of material of the main cover to removably connect the envelopes thereto, and a strap member connected to the flexible portion of the extensible member and adjustably connected to another portion of said extensible member for holding the cover members in closed position.

5. An extension cover holder, comprising a main cover member formed of two thicknesses of material joined together at their opposite ends, the inner edge portion of the inner thickness of material having eyelets, an extensible cover member having a firm portion and a flexible portion, said flexible portion extending between the two thicknesses of material for adjusting the distance apart of said main cover and the firm portion of the extensible cover, envelopes removably positioned between the covers and having eyelets registering with the eyelets of the inner thickness of material of the main cover, a string extending through the registering eyelets of the main cover and the envelopes and adjustably tied together at its end portions to removably connect the envelopes to the cover portion, a buckle mounted on the extensible cover portion, and a strap connected to the flexible portion of the extensible cover member and adjustably engaging the buckle.

In testimony whereof, I affix my signature.

HENRY SEELMAN.
